FOILING DEVICE FOR WAX DENTURES

James J. Dwyer, Philadelphia, Pa.

Application April 29, 1939, Serial No. 270,940

5 Claims. (Cl. 18—5.7)

This invention relates to the manufacture of dentures in which the artificial teeth are mounted in a plate formed of a molded plastic, certain of which plastics must, in the process of manufacture, be prepared in molds which are lined with an impervious substance such as tin-foil which is chemically inert toward the plastic.

The usual practice is to apply the tin-foil to the mold by hand and to smooth it down and fit it into the surface irregularities. Apparatuses have been devised for mechanically foiling the wax denture from which the mold is formed but all of these apparatuses with which I am familiar are of such nature that they either do not smoothly affix the foil to the denture or into the irregularities thereof, due primarily, to the fact that they do not properly conform to the denture prior to the application of pressure through which the actual foiling operation is accomplished. Furthermore, wax dentures are fragile and the strain placed thereon unless evenly applied has a tendency to deform the same. Additionally, these devices require the use of excessive pressure, cannot be employed in foiling dental casts or models without flasking the same and ordinarily employ a rigid mounting for the flask requiring separate fixtures for use with flasks of different sizes.

Important objects of the present invention are the production of a device which may be utilized in foiling such dentures, which is so constructed that pressure is applied uniformly about the denture, mold or cast, which is so constructed that it may be utilized with equal facility on shallow or deeply arched dentures, which may be employed in foiling with or without a flask and which will accommodate flasks of various sizes.

Another object of the invention is the production of a device of this character which may be cheaply manufactured and in which the foiling may be accomplished with the use of much less pressure than that heretofore considered necessary.

These and other objects I attain by the construction shown in the accompanying drawings wherein, for the purpose of illustration, I have shown a preferred embodiment of my invention and wherein:

Fig. 1 is a combined perspective partially in section illustrating a foiling device constructed in accordance with my invention;

Fig. 2 is a sectional view through the composite fluidly resilient member by which pressure is directly applied to the denture and foil;

Fig. 3 is a bottom plan view of the main body of the pressure-applying member;

Fig. 4 is a perspective of the removable filler

piece employed with the composite pressure-applying member under certain circumstances;

Fig. 5 is a sectional view through the mold in the process of foiling a deeply arched or lower denture;

Fig. 6 is a similar view showing an apparatus in use for foiling a shallowly arched or upper denture;

Fig. 7 is a perspective of the filler ring employed about the dental flask;

Fig. 8 is a section similar to that of Fig. 5, showing the foiling process prior to the application of pressure;

Fig. 9 is a section on line 9—9 of Fig. 2;

Fig. 10 is a perspective view showing the insert employed when foiling dental casts or models without the use of a flask; and

Fig. 11 is a sectional view through the foiling device illustrating foiling of a dental cast without the use of a flask.

Referring now more particularly to the drawings, the numeral 10 designates a dental flask containing either a wax impression D of an artificial denture, or a dental cast I conforming to one side of the proposed denture, and 11 a metallic container for the flask having an internal diameter larger than the flask. About the flask

I arrange a highly resilient ring 12 which conforms to the outer surface of the flask and to the inner surface of the container 11. Within the container I impose upon the flask a fluidly resilient pressure element comprising a main body 13 and a molded insert 14 adapted to fit within and conform to the shaping of a recess 15 formed in the under surface of the main body and conforming substantially to the shaping of an artificial denture having a relatively deeply arched formation such as a lower plate.

The main body has a depression 16 in its upper surface so formed that the cross section of the main body upon any diameter is, as nearly as possible, uniform and of substantial thickness with the filler member 14 removed. Insert 14 is, of course, formed of the same material as pressure element 13.

A cap 17 is provided through which pressure may be applied to the pressure-applying member 13, this cap having its inner surface formed to conform to the shaping of the upper surface of the pressure-applying member

13. It will be obvious that, due to the fact that the material of pressure element 13 and the insert 14 is fluidly resilient and, due to the fact that by use or omission of the insert 14 the pressure element can be made to conform very nearly exactly to the contour of the member to be foiled,

that pressure will be uniformly applied about the surfaces of the denture or cast and the foil will, accordingly, be smoothly forced in position thereagainst. Furthermore, due to the use of the highly resilient ring 12 the flask 10 may shift within the container 11 to properly centralize itself to imposed pressures, thus avoiding application of the severe side strains resulting from the use of fixed structures.

10 In addition to foiling devices contained in flasks it is also possible to foil dental casts or models without placing the same in a flask, this being illustrated in the sectional view forming Figure 11. In performing this operation the 15 insert 18 illustrated in Figure 10 is utilized within the ring 12 this insert conforming in size and shape to the opening of the ring. As a matter of fact, in practice the ring 12 and insert 18 are shipped as a solid disc from which the insert is 20 cut in accordance with the size of flasks employed by the user. Upon the disc formed by the combination of ring 12 and insert 18 the dental cast 20 is seated and the pressure member 13 or this member in combination with the insert 14 employed depending upon the nature of the cast which is to be foiled. Since a resilient base is 25 provided for the cast and this base has the same resiliency and characteristics as the pressure-applying member, it is obvious that inequalities 30 in pressure which otherwise would result in breakage of the cast will be avoided.

It is to be understood that the term "denture" as employed in the appended claims comprises dental impressions and casts therefrom as well 35 as waxed-up dentures.

Since the structure is capable of considerable modification without departing from the spirit of my invention, I do not wish to be understood as limiting myself to the arrangement herein 40 specifically illustrated except as hereinafter claimed.

I claim:

1. In a foiling device for waxed-up dentures and the like comprising a flask receiving the denture, a rigid receiver loosely surrounding the flask, a resilient filler peripherally encompassing the flask and loosely fitting within the receiver, a cap interiorly constructed to substantially conform to the shape of the exposed face of the denture and of substantially uniform thickness in directions perpendicular to the denture and a rigid member interiorly fitting the receiver and conforming to the shape of the cap through which pressure may be applied to the denture 50 through the cap, said cap being formed of mate-

rial having the inherent characteristics of soft rubber.

2. In a foiling device for waxed-up dentures and the like comprising a support for the denture, a rigid receiver for the support and denture, a cap interiorly constructed to substantially conform to the shape of the exposed face of the denture and of substantially uniform thickness in directions perpendicular to the denture and a rigid member interiorly fitting the receiver and conforming to the shape of the cap through which pressure may be applied to the denture through the cap, said cap being formed of material having the inherent characteristics of soft rubber.

3. In a foiling device for waxed-up dentures and the like comprising a support for the denture, a rigid receiver for the support and denture, a cap interiorly constructed to substantially conform to the shape of the exposed face of the denture and of substantially uniform thickness in directions perpendicular to the denture and a rigid member interiorly fitting the receiver and conforming to the shape of the cap through which pressure may be applied to the denture through the cap, said cap and support being formed of material having the inherent characteristics of soft rubber.

4. In a foiling device for waxed-up dentures and the like comprising a support for the denture, a rigid receiver for the support and denture, a cap having its inner face grooved to substantially conform to the shape of the exposed face of the denture and of substantially uniform thickness in directions perpendicular to the denture, a rigid member interiorly fitting the receiver and conforming to the shape of the cap through which pressure may be applied to the denture through the cap, and a filler for said groove, said cap and filler being formed of material having the inherent characteristics of soft rubber.

5. In a foiling device for waxed-up dentures and the like comprising a support for the denture, a rigid receiver for the support and denture, a cap having its inner face grooved to substantially conform to the shape of the exposed face of the denture and of substantially uniform thickness in directions perpendicular to the denture, a rigid member interiorly fitting the receiver and conforming to the shape of the cap through which pressure may be applied to the denture through the cap, and a filler for said groove, said cap support and filler being formed of material having the inherent characteristics of soft rubber.

JAMES J. DWYER. 55
